UNITED STATES PATENT OFFICE.

LORING L. LEEDS, OF SHORT HILLS, NEW JERSEY, ASSIGNOR TO FRANK M. NEEDHAM,
OF CHICAGO, ILLINOIS.

RECORDER AND REPRODUCER FOR TALKING-MACHINES.

1,296,975.

Specification of Letters Patent. Patented Mar. 11, 1919.

Application filed January 31, 1916. Serial No. 75,271.

To all whom it may concern:

Be it known that I, LORING L. LEEDS, a citizen of the United States, and resident of Short Hills, in the county of Essex and State 5 of New Jersey, have invented certain new and useful Improvements in Recorders and Reproducers for Talking-Machines, of which the following is a specification.

My present invention relates to the sound 10 boxes of talking machines, and has for its object to improve the connection between the sound box and the bar or socket which supports the reproducing or recording stylus. My improved connection is of a very firm 15 yet elastic character and insures a clear reproduction of sounds with a minimum of disturbing noises.

A specific example of my invention is shown in the accompanying drawings, in 20 which Figure 1 is a side elevation of a recorder or reproducer embodying my invention; Fig. 2 is a front view thereof; Fig. 3 is a partial vertical section on line 3—3 of Fig. 4; Fig. 4 is a partial vertical section 25 on line 4—4 of Fig. 3; Fig. 5 is a front elevation and Fig. 6 a side elevation of a block forming part of my invention; Fig. 7 is a face view, and Fig. 8 an edge view of a cup forming part of my invention.

The body 11 of the sound box, with the 30 diaphragm 12 and the sleeve or sound-conducting tube 13, are constructed in any customary or approved manner. On one side of the body 11 are projected two (parallel) 35 lugs 14, preferably integral with said body, and provided with alining transverse apertures 14' threaded to receive screws 15. The inner ends 15' of these screws are tapered or pointed, while their outer ends 15'' are 40 preferably slotted so that they may be turned readily by means of a screw-driver. To hold the screws in their adjusted position, nuts 16 may be screwed against the outer faces of the lugs 14.

The inner ends of the screws 15 fit into 45 recesses or holes 17' provided at the center of cups 17 made of steel or other elastic material, these cups being quite thin and dished to give them considerable elasticity 50 which may be further increased by slitting the cups from the periphery inward, as indicated at 17''. The convex faces of the cups 17 are directed toward the lugs 14, and the edges or peripheries of said cups are seated 55 upon opposite sides of a block 18 which

forms part of the stylus-support. The block has circular recesses as shown, best in Fig. 6, to receive the cups 17, and projections 18' are thus formed at the corners to hold the cups against lateral movement (see Figs. 5 60 and 6). The block is preferably also formed with a transverse aperture or passage 18'' which connects the two recesses in which the cups 17 are seated. An extension 18a of the block 18 is provided with a perforation 65 (see Figs. 3 and 6) through which extends the stylus arm 19 screwed to the diaphragm 12 in the usual manner and provided with a socket 19' and clamping screw 20 to hold the point or stylus 21. The stylus arm, is 70 secured to the block, 18 rigidly, in fact, these two parts might be made one integral with the other.

It will be seen that the connection of the stylus arm 19 and of its block 18, with the 75 body 11 of the sound box, is very firm, yet elastic, the cups 17 being capable of yielding slightly, in every direction, the dished form and the slitting of these cups at 17'' giving them a high degree of elasticity. In 80 connection with the recesses upon which they are seated, these cups 17 form air-chambers (see Fig. 4) connected by the passage 18'', and the body of air contained in these chambers and passage forms a cushion further increasing the elastic action of the cups 17. This body of air is in communication 85 with the surrounding air, by means of the slits 17''. The elastic tension of the cups may be increased or decreased as desired 90 by a longitudinal adjustment of the screws 15 in the apertures 14'.

The construction described is relatively 95 simple and insures a firm, yet elastic connection, the sound being reproduced clearly and with a minimum of disturbing noises.

Various modifications may be made without departing from the nature of my invention as set forth in the appended claims.

I claim:

1. A sound-box for talking machines, comprising a body with two lugs projected therefrom and provided with alining screw-threaded apertures, screws adjustable in said apertures, nuts for locking said screws, a 105 stylus-supporting bar having a block provided with recesses in the faces adjacent to the ends of the screws, and with a passage connecting said recesses, and elastic cups seated in said recesses and having their con- 110

vex surfaces toward the adjacent lugs, said cups having central recesses to receive the ends of the screws, and slits at the periphery to increase their elasticity.

- 5 2. A sound-box for talking machines, comprising a body, spaced alining members carried by said body, a stylus-support extending between said members, and elastic cups, slitted at their peripheries, interposed between the inner ends of said alining mem-

bers and the adjacent faces of the stylus-support.

In testimony whereof I have signed this specification in the presence of two subscribing witnesses.

LORING L. LEEDS.
